UNITED STATES PATENT OFFICE.

CHARLES ALLAN GILBERT, OF NEW YORK, N. Y.

MANUFACTURE OF MOVING-PICTURE FILMS.

1,279,099.

Specification of Letters Patent. Patented Sept. 17, 1918.

Application filed April 20, 1915. Serial No. 22,556.

To all whom it may concern:

Be it known that I, CHARLES ALLAN GILBERT, a citizen of the United States, residing at 26 Eighth street, New York, county 5 of New York and State of New York, have invented certain new and useful Improvements in the Manufacture of Moving-Picture Films, fully described and represented in the following specification and the accompanying drawings, forming a part of the same.

The present invention relates primarily to an improved process for making a moving picture film to show an entire play produced in silhouette.

The process may be practised by certain steps which permit the silhouettes to be obtained without casting shadows of the actors, and the film may, in addition to the moving 20 figures of the actors, be provided with scenes photographed from drawings, which may be made to exhibit objects in a relation to the actors which could not be secured by photographing any natural objects.

25 In practising the invention, photographs of actors whether silhouette or shaded, may be made upon one moving film, and photographs of drawings upon another moving film, and a composite film obtained by combining the two films together, or printing through both simultaneously upon the working film.

This process of producing a film possesses a great advantage, in permitting photographs of moving actors to be associated with a back-ground or scenery, as a forest or building, which can be photographed from small drawings independently of the actors, and thus avoid the construction of 40 expensive scenery or the transportation of the actors to natural scenes of the desired character.

The process also permits photographs of moving actors to be associated upon the composite film with photographs of apparently moving objects of unnatural, artificial, or preposterous character, such as latter scenes can be readily photographed on a preparatory film from a succession of drawings of 45 moderate size, showing the different positions and changes of such artificial objects.

The invention also includes as a new article of manufacture a film provided with photographs of silhouettes, also a composite 55 film provided with photographs of silhouettes,

ettes, associated with photographs of drawings, also a composite film provided with photographs showing silhouettes of actors combined with photographic silhouettes taken from drawings. 60

The invention will be understood by reference to the annexed drawing, in which Figure 1 is a representation of one view upon a composite moving picture film having scenery and the silhouettes of actors derived 65 from different films; Fig. 2 shows portion of a film with views of two moving actors; Fig. 3 shows portion of a film having trees photographed from a back ground; Fig. 4 shows a composite film printed from the 70 films of Figs. 2 and 3; Fig. 5 represents three successive views of a moving animal photographed from drawings; Fig. 6 represents three successive photographs of a moving actor; Fig. 7 represents three views 75 from a film derived from the photographs of Figs. 5 and 6; Fig. 8 represents a portion of a film with two successive views of a moving actor; Fig. 9 represents a portion of a film with two successive views of a 80 bird photographed from drawings; Fig. 10 represents two views upon a composite film printed from the films of Figs. 8 and 9; Fig. 11 is a view in sequence with the views of Fig. 10, and photographed from a drawing 85 representing a scene which could not exist in reality; Fig. 12 is a front view of a screen and stage with the equipment for photographing silhouettes; and Fig. 13 is a rear view of the attachments for the illuminated 90 screen.

Fig. 1 represents a single view upon a composite film printed from two other films.

A designates a back ground of buildings photographed from a drawing upon a moving film, the operation producing successive identical views of the back ground, upon a suitable scale for association with the figures B which are shown in silhouette before the buildings, and which are photographed 95 upon a separate moving film; and the view of Fig. 1 is produced by printing through both the films upon the composite working film.

The drawing for the back ground may 105 obviously be made of any desired size and the view may be made as elaborate as desired, and may be made to show the details of objects as shown in Fig. 1; or, if preferred, may be made in solid black repre- 110

senting silhouettes of the objects, as the trees *d* are in Fig. 3.

The preparatory films will be termed "partial films" herein, as they exhibit only 5 a portion of the scenes required for the working film.

Fig. 2 shows one view upon a partial film taken from two actors *c* engaged in fencing; Fig. 3 shows one view, upon a partial film, 10 of trees *d* photographed from a drawing upon a scale adapted to coöperate with the views of the actors' figures *c*; and Fig. 4 shows one view from a composite film printed jointly and simultaneously from the films 15 of Figs. 2 and 3.

A bird *e* is shown in the views of Figs. 3 and 4, which may be represented as moving by drawing or printing a series of tree-groups shown in Fig. 3, with the bird delineated in successive positions upon the successive views to express its flight across the scene.

To avoid duplicating the drawing of the trees, the bird may be represented of some 20 suitable material separate from the drawing of the trees, and moved across such drawing when the partial film of the trees is made.

Fig. 5 represents three views from a partial film photographed from a series of drawings showing an elephant *m* in successive positions.

Fig. 6 shows three views from a partial film photographed from a moving actor *m'*; Fig. 7 shows three views from a composite film made from the films of Figs. 5 and 6, showing an acting elephant and his trainer.

Fig. 8 shows part of a film with two views 40 of a moving actor *p* and the adjacent spaces vacant; Fig. 9 shows two views of successive positions of a large bird *o'* taken from drawings; and Fig. 10 shows two views of a composite film printed from the films of Figs. 45 8 and 9. Such composite film shows the bird vastly greater than the man, and to produce a further effect not obtainable from nature, the composite film thus made is joined to another made wholly from drawings, in 50 which the bird *o'*, as shown in Fig. 11, is represented as flying away with the man *o*.

It is obvious that the invention secures, by very simple means, a composite film displaying in its successive views photographs 55 of moving actors combined with photographs of objects represented in drawings, thus producing many results or effects not attainable in any other manner.

The actors and objects represented in the 60 different figures of the annexed drawing are most of them shown in solid black to represent silhouettes of such actors and objects, but the processes described herein are capable of photographing the actors with detail 65 by illuminating them in the usual manner.

The use of silhouettes has, however, a peculiar interest, as silhouettes produce an appearance quite different from that of living actors, because the silhouettes possess no characteristics of life except their mere movement.

By also representing silhouettes of a background or objects associated with the moving actors, a very weird and unusual effect is produced, as of black people moving in a 75 black world.

It is well known that silhouettes can be produced by shadows, but that shadows do not exhibit a sharp image unless the object is close to the screen which receives the shadow, 80 and as moving pictures could not be taken of a shadow under such conditions, I have devised a means of directly photographing the actors, to present the appearance of silhouettes, by having their movements performed in front of an illuminated screen, that is between the screen and the camera, so that the side of the objects toward the camera is in the dark, but the objects themselves, rather than their shadows, are photographed. One method of securing this desired effect is to mount an ordinary muslin or linen screen at the back of the stage or platform upon which the actors perform and provide means whereby it is highly 95 illuminated from the back. The front presents a bright light surface, against which the figures of the actors appear precisely like shadows but having the same sharpness and distinctness of outline as ordinary film pictures, and possessing a depth of black color not attainable in shadows due to the fact that all of the light is on the side of the objects away from the camera. In some instances, I may, if desired, blacken 105 the faces and clothing of the actors, but this is not necessary if there is no other illumination than that which is behind the actors and employed solely for illuminating the screen.

Fig. 12 is a perspective view of a stage *g* upon which actors *h* can move before a translucent screen *i* behind which lights *j* are arranged to give the necessary illumination without throwing direct rays through the screen.

The screen constitutes the front of a species of box or small chamber in which the light is confined so as not to produce any lighting effect in front of the screen.

This box is furnished with wooden side 120 wings *l* carrying banks of electric lights *j* which operate to illuminate the rear side of the screen.

The edges of the screen are extended in opaque strips *l'* which join the forward 125 edges of the wooden wings *l* and effectively confine the strong light to the box. A roof *n* also assists to confine the light. Although no shadows of the actors fall upon the screen with the above arrangement, the relation of 130

the actors to one side of the screen is indicated by dotted lines in Fig. 13.

This means of producing silhouettes obviously presents enormous advantages, as it gives the actors entire freedom of movement without reference to the illuminating agent, which is impossible if actors move between a light and a screen to cast shadows thereon.

10 It also permits the camera to be placed in any convenient location to photograph the actors, which would not be possible with actors between the screen and the illuminant. By having the camera with its eye-piece approximately on the level of the stage or platform, the upper surface of said stage or platform will not appear in the photograph. Therefore, the feet of the actors and the lower portion of objects on the platform will 15 appear as clear and distinct when the actors are up-stage as when they are back close to the screen. As the pictures are in solid color so that details on the surface toward the camera do not show, an object or an actor 20 may be made to apparently change in size by moving toward or from the camera.

Such process of photographing moving actors would operate the same whether the actors were blackened or not, and a drawn 25 back-ground could thus be combined with moving actors without having the actors in silhouette.

The lower parts of the drawing would be 30 left white, so that lines would not show through in combining the partial films.

As the apparatus for taking moving pictures in resemblance of silhouettes is required to practice my invention, I have made claim to the same herein.

40 It is evident that by the means described herein silhouettes may be produced with a light body as well as with a black body, and that the back ground in such case could be black or colored instead of white, and the 45 drawings to combine with such silhouette could be made with similar characteristics so that the moving pictures thrown upon the screen would appear as white actors or white objects moving before a black or colored 50 back ground.

The term silhouettes, where used in the claims, is therefore to be understood as meaning the body of a moving actor, or any object represented by a drawing without 55 shading or details upon its surface.

To produce white silhouettes, the actors or objects would be placed before a black or dark screen and illuminated in a general way so as to cast no shadows thereon, and 60 photographs upon a moving film can be made of such objects and screen, which present white or light bodied silhouettes.

Where the photographs on the film depict white objects upon a black back ground it is evident that the pictures and back ground 65 would be the reverse of those produced in photographing black figures upon a white back ground, and the film could therefore be used directly for projecting the moving pictures instead of in the usual manner as a 70 negative.

Where white silhouettes of actors are to be shown with white objects represented in drawings, the combination of such silhouettes with the drawings of objects can also be effected in the same manner as when black 75 silhouettes and black objects are photographed upon the moving film.

Having thus set forth the nature of the invention what is claimed herein is:

1. A process of producing moving picture films which consists in photographing moving actors in silhouette on one negative film, photographing a series of drawings showing an object in successive positions and in silhouette on another negative film, and producing a positive film from both of said negative films with silhouettes of the actors and of the drawn objects in predetermined relative positions to form a series of composite film pictures in silhouette. 80

2. A process of producing moving picture films which consists in photographing on one negative film moving actors in solid black against an illuminated background, photographing on another negative film a series of drawings in solid black on a light background each showing an imaginary object but in a slightly altered position from that of the preceding drawing, and producing a 90 positive film from both of said negative films and with the silhouettes of the actors and the drawn pictures of the imaginary objects in predetermined relative positions to form a series of film pictures all of the figures of which are in solid color. 95

3. A process of producing moving pictures each showing in solid color on a light background both a real animated and an imaginary moving object, said process including photographing on one film said real animate object in solid black against an illuminated background, photographing on another film a series of drawings each showing the same object in successive positions, and utilizing said first and second mentioned films to produce by printing a third film showing a series of film pictures each including solid color representations of said real and said imaginary objects in predetermined relative positions. 100

In testimony whereof I have hereunto set my hand.

CHARLES ALLAN GILBERT.
